[57] CLAIM

The ornamental design for a bathroom faucet set, substantially as shown and described.

DESCRIPTION

FIG. 1 is a front elevational view of a bathroom faucet set showing my new design;

FIG. 2 is a top plan view thereof;

FIG. 3 is a bottom plan view thereof;

FIG. 4 is a rear elevational view thereof; and

FIG. 5 is a left side elevational view of the spout portion thereof, the right side being a mirror image of the left side shown.

FIG. 2

FIG. 3

FIG. 5
